UNITED STATES PATENT OFFICE.

EDWIN A. HAYDEN, OF SALT LAKE CITY, UTAH.

NONREFILLABLE BOTTLE.

1,420,545.

Specification of Letters Patent. Patented June 20, 1922.

Application filed October 15, 1920. Serial No. 417,154.

To all whom it may concern:

Be it known that I, EDWIN A. HAYDEN, a citizen of the United States, residing at Salt Lake City, in the county of Salt Lake and State of Utah, have invented certain new and useful Improvements in Nonrefillable Bottles, of which the following is a specification.

This invention relates to new and useful improvements in non-refillable bottles, the primary object of the invention being to provide a device of this nature in the form of a stopper adapted for insertion in the neck of a bottle to prevent unauthorized refilling of the bottle after the contents thereof have been once dispensed.

An important object of the invention is to provide improved means for locking the stopper within the neck of the bottle.

Another object of the invention is to provide a stopper of a configuration which will prevent the valve therein from being tampered with to cause refilling of the bottle.

Still another object of the invention is to provide a stopper having an upwardly opening valve therein and means associated with the valve for automatically closing the same.

Other objects and advantages of the invention will become apparent during the course of the following description.

In the accompanying drawings forming a part of the application and wherein like numerals are employed to designate like parts throughout the several views—

Figure 1 is a section of a bottle neck with my improvements embodied therein.

Figure 2 is a sectional view of the invention applied to the bottle neck.

Figure 3 is a bottom plan of the stopper, and

Figure 4 is a top plan of the same.

Referring to the drawings wherein for the purpose of illustration is shown the preferred embodiment of the invention, the numeral 5 designates the neck of an ordinary bottle or receptacle, the interior wall of which is provided with an L-shaped slot or channel 6, the vertical arm of which extends from the upper end of the neck downwardly a substantial distance. The horizontal arm 7 of the slot is a trifle shorter than the vertical arm and at the juncture of these two arms of the slot, an inwardly swinging closure member 8 is pivoted. It will be noted

that the upper edge of the member 8 is pivotally connected adjacent the relative upper end of the horizontal portion 7 of the slot and the relative lower end of the member 8 normally abuts with a shoulder 9 formed in the lower edge of the slot 7 so that the outward swinging movement of the member 8 is precluded. However, it will be noted that the member 8 may swing inwardly of the slot for a purpose which will hereinafter appear. The upper end of the vertical arm 6 of the L-shaped slot 6 is also provided with a closure member 10 identical in construction to the member 8. The edge of the vertical arm of the slot opposite that to which the member 10 is pivoted is provided with a shoulder 11 to prevent outward or upward swinging movement of the member 10. However, it will be noted that the member 10 may swing downwardly or inwardly of the slot the same as the member 8.

The stopper or closure 12 is hollow and is of a size to fit within the neck. At a suitable point on the exterior of the stopper I provide an outwardly extending projection 13 which is adapted to move inwardly of the L-shaped slot 6 and move the slot closing members 8 and 10 inwardly when the stopper is assembled with the bottle neck. It is to be understood that there will just be enough space at the inner extremity of the L-shaped slot to permit of entrance of the projection 13 and clearance of the member 8 so that when the stopper has once been assembled with the bottle, it cannot be removed.

A partition 14 extends across the stopper at a substantial distance below the top thereof and is provided with a central aperture 15, the edges of which are counter-sunk. A valve 16 is hinged at one end to the edge of the aperture in the partition and the edges thereof are beveled to fit the counter-sunk edges of the opening whereby the top of the valve will be flush with the top of the partition and consequently will preclude opening of the valve with means inserted down through the stopper. A weight 17 in the form of a bar is secured to the underside of the valve to normally close the same after the bottle has been placed in an upright position after dispensing the contents thereof.

The upper portion of the stopper 12 is formed with an enlarged concentrically ar-

ranged head 18, the lower edges of which rest upon the top edge of the bottle neck. A spout 19 projects laterally from the head of the stopper and communicates therewith 5 at an eccentrically arranged point so that it is impossible to insert a wire or other implement through the spout and tamper with the valve 16. A cap 20 of any desired construction is adapted to be received upon the 10 open outer end of the spout 19 to prevent air from gaining access to the contents of the bottle.

When it is desired to dispense the contents of a bottle, embodying my invention, 15 the cap 20 of the spout is removed and the bottle is then tilted in the usual manner. The contents of the bottle will of course force the valve 16 outwardly and flow through the hollow stopper 12 out through 20 the spout 19. When the bottle is returned to an upright position to stand upon its base, the weight 17 on the valve will automatically close the same. It will of course be obvious that it is impossible to remove the stopper 25 from the neck of the bottle without breaking the latter.

The foregoing description and the accompanying drawings have reference to the preferred or approved embodiment of my invention. It is to be understood however that 30 such changes may be made in construction and arrangement of parts, materials dimensions, etc., as may prove expedient and fall within the scope of the appended claims.

35 Having thus fully described my invention

what I claim as new and desire to secure by Letters Patent is:—

1. The combination with a bottle neck, and retainer means associated with the top of the neck for preventing removal of a 40 stopper therefrom; of a hollow valved stopper for the neck, said stopper having an enlarged concentrically disposed head to overlap the top of the bottle neck and said retainer means and a spout extending from 45 said head.

2. The combination with a bottle having a slot in the interior surface of the neck thereof, an inwardly swinging member having limited inward movement in said slot and 50 being precluded from outward movement of the neck; of a valved stopper having a projection movable in the slot and prevented from release therefrom by said inwardly swinging member.

3. The combination with a bottle having an L-shaped slot in the interior surface of the neck thereof, inwardly swinging members at the top and at the angular portions of said slot, and a valved stopper having a 60 projection adapted to be moved into the bottom of said slot, and prevented from removal therefrom by said members.

In testimony whereof I affix my signature in presence of two witnesses.

EDWIN A. HAYDEN.
